EXPANSION JOINT

Charles C. Bargreen, Streator, Ill.

Application September 4, 1931, Serial No. 561,286

5 Claims. (Cl. 94—18)

This invention relates to certain new and useful improvements in expansion joints.

The primary object of the invention is to provide an expansion joint of the character employed in the laying of roads to compensate for expansion and contraction of the material comprising the road so that such expansion and contraction may take place without resulting in cracks or fissures appearing in the road.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a top plan view of an expansion joint for hard roads, the joint being constructed of sections and extending the full width of the road;

Figure 2 is a bottom plan view of the expansion joint;

Figure 3 is a side elevational view of the joint;

Figure 4 is an end view showing the parts embedded in the adjacent pavement sections;

Figure 5 is a cross-sectional view taken on line 5—5 of Figure 3 showing the parts embedded in adjacent pavement sections;

Figure 6 is a cross-sectional view taken on line 30 6—6 of Figure 3 showing the parts embedded in adjacent pavement sections.

The expansion joint disclosed herein is designed for use in the construction of roads so that the material of the roads may expand and contract with damage to the roads eliminated, the expansion joints being positioned certain distances apart to compensate for expansion of the road materials. The expansion joint comprises a pair of spaced angle members extending the full width of the road, each angle member comprising a vertical wall 10 carrying an outwardly directed horizontal wall 11 at its upper edge with the outer edge of the wall 11 flanged upwardly as at 12. The walls 10 are spaced from each other as illustrated in Figures 5 and 6 while the horizontal walls 11 disposed in the same plane provide a seat for the tread plate 13 that has a roughened surface 13a as shown in Figure 1, comprising diamond-shaped formations to prevent skidding, the tread plate being loosely mounted upon the horizontal walls 11. The tread plates 13 are formed in sections and as illustrated in Figure 1, they extend the full width of the road bed.

A channel iron 14 is positioned between the upper ends of the walls 10 of the angle members

and the several tread plates 13 are secured thereto in any preferred manner, the closed side of the channel iron 14 having the tread plate secured thereto with the open side thereof directed downwardly for the reception of the cross-head 15 of the depending T-iron 16. The T-iron constitutes a part of guide devices for movement of the angle irons comprising the walls 10 and 11, the T-irons having spaced openings 17 therein for the passage of rods 18 that also extend through aligned openings 19 provided in the walls 10. The outer ends of the rod 18 are received in sleeve members 20 embedded in the road material while coil springs 21 surrounding the rod 18 between the T-iron 16 and walls 10 maintain the walls 10 of the angle irons properly positioned relative to the material of the road bed. Tie rods 22 are secured as at 23 to the walls 10 of the angle irons and are embedded in the road. As shown in Figures 1 to 4, an end wall 24 is hinged as at 25 to the outer ends of the end tread plate 13 to provide closures for the ends of the expansion joint and are retained in closed position by bolt and nut devices 26 forming connection between the end wall 24 and the T-iron 16.

From the above detailed description of the invention, it is believed that the construction and operation thereof will at once be apparent, it being noted that the angle members comprising the walls 10 and 11 are shiftable during expansion and contraction of the road material, moving under the tread plates 13 and guided in their movements on the rods 18, the spring devices 21 serving to correctly position and hold in proper position the plates 13 at all times with respect to the angle members 10 as they are moved back and forth due to the contraction and expansion of the road material.

While there is herein shown and described the preferred embodiment of the invention, it is nevertheless to be understood that minor changes may be made therein without departing from the spirit and scope of the invention as claimed.

I claim:—

1. An expansion joint for pavements to be located between adjacent pavement sections comprising a pair of separated angle members having substantially vertical walls and upper horizontally disposed walls the horizontal walls being directed away from each other, means for anchoring the angle members to the contiguous pavement sections, a tread plate loosely mounted on the upper horizontally disposed walls, a channel iron connected with the bottom of the tread plate, a T-iron connected with said chan-

nel iron and projecting down between the angle members and a rod extending through the angle members and the T-iron, and opposing spring members mounted between the vertical flanges 5 of the angles and the stem of T-iron to hold the latter in operative position.

2. An expansion joint for roads, comprising separated adjacent pavement sections, a pair of angle members inserted in the road bed between 10 the adjacent pavement sections and crosswise of the pavement, means for holding said members in correct position with relation to said adjacent pavement sections and shiftable during expansion and contraction of the road bed, a 15 tread plate loosely mounted on top of the angle members, a downwardly projecting member connected with said tread plate and projecting between the angle members, and a rod extending through the angle members and the downwardly 20 projecting member which keeps the members in proper vertical relationship, said rod being free to move horizontally with respect to the vertical angle members, whereby the various elements cooperate with the separated adjacent pavement 25 sections to compensate for expansion and contraction due to variations in temperature.

3. An expansion joint for roads, comprising separated adjacent pavement sections, a pair of shiftable members in spaced relation, adapted to 30 be inserted in the roadway between the adjacent pavement sections and crosswise of the pavement, springs mounted between said members, a rod extending through said members and said springs, and guiding devices mounted in the 35 separated adjacent pavement sections into which the ends of said rod are received, said rod holding said shiftable members in proper vertical relationship but free to move horizontally with respect to said shiftable members, whereby the various elements cooperate with the separated adjacent 40 pavement sections to compensate for expansion and contraction due to variations in temperature.

adjacent pavement sections to compensate for expansion and contraction due to variations in temperature.

4. An expansion joint for roads, comprising separated adjacent pavement sections, a pair of shiftable members in spaced relation, adapted to 5 be inserted in the roadway between the adjacent pavement sections and crosswise of the pavement, springs mounted between said members, a rod extending through said members and said 10 springs, and guiding devices mounted in the roadway into which the ends of said rod are received, a tread plate mounted on said members, said rod holding said shiftable members in proper 15 vertical relationship but free to move horizontally with respect to said shiftable members, whereby the various elements cooperate with the separated adjacent pavement sections to compensate for expansion and contraction due to variations in temperature. 20

5. An expansion joint for roads, comprising separated adjacent pavement sections, a pair of shiftable members in spaced relation, adapted to 25 be inserted in the roadway between the adjacent pavement sections and crosswise of the pavement, two coacting springs mounted between said members and normally tending to press them apart, a rod extending through said members and said springs, and guiding devices mounted in the roadway into which the ends of 30 said rod are received, said rod holding said shiftable members in proper vertical relationship but free to move horizontally with respect to said shiftable members, whereby the various elements cooperate with the separated adjacent 35 pavement sections to compensate for expansion and contraction due to variations in temperature.
